UNITED STATES PATENT OFFICE.

ANDREW THOMA, OF CAMBRIDGE, MASSACHUSETTS, ASSIGNOR TO NORTH AMERICAN CHEMICAL COMPANY, A CORPORATION OF MAINE.

SHOE-BOTTOM FILLER.

1,202,454.

Specification of Letters Patent. Patented Oct. 24, 1916.

No Drawing.

Application filed March 21, 1910. Serial No. 550,802.

To all whom it may concern:

Be it known that I, ANDREW THOMA, a citizen of the United States, and resident of Cambridge, in the county of Middlesex, and State of Massachusetts, have invented an Improvement in Shoe-Bottom Fillers, of which the following description is a specification.

The object of my present invention is to provide a shoe filler material which is unlike the material at present in use, in that it possesses a great amount of resiliency (*i. e.* cushion-like effect in a shoe), equaling, if not surpassing, the resiliency of the pure and best grades of rubber in sheet form.

My intention is to use, in place of the usual granulated form of cork, leather dust, ground leather, or similar dissected material for a filler-body, a mass of coagulated oil, which, when prepared for my particular purpose, resembles a mass of crawling maggots when disturbed.

The coagulated ground oil can be prepared in various ways so that its shredded particles may be firm and dry, or its process of treatment may be one to allow a certain softness to the mass which also gives the pulp a slight cohesive nature. In other words, the pulp is not dry and lifeless, but full of life, easily admixed to suitable binding agents, and readily spread within the shoe cavity.

Various methods may be pursued to solidify bodies of various vegetable oils. It may be done by a simple prolonged boiling process, or it may be brought about by sulfurizing or treatments with acids. The methods of oxidizing of oils are so numerous that it is not necessary for me to enumerate them. It is primarily the product which enters in a ground, shredded, or otherwise dissected state into my novel filler material that is of importance here. To render this crawling ground oil matter fit to be readily workable so as to form a resilient, compact layer within a shoe bottom; to make it quickly conformable, adhesive and cohesive without destroying its resiliency is the second feature of my invention. For this purpose I use a binding material such as is described in my patent No. 945,294, dated January 4, 1910, (which is subordinate to my foundation or pioneer filler Patent, No. 832,002 of Sept. 25, 1906)—viz. a permanently elastic, quicksetting, sticky mass containing a gelat-

inous base. For instance, I may use one and a half ounces of pure casein, one quarter ounce of borax, six ounces of water, one half ounce of glycerin (all dissolved in a water bath into a smooth flowing solution), five 60 ounces of rosin (naphthalene-dissolved), two ounces wax tailings (petroleum), and one third ounce of Wilmington tar; or, eight ounces of bone glue, three ounces of glycerin, eight ounces of water, two ounces of calcium 65 chlorid, heated to 160 degrees F., and dissolved into a smooth flowing, permanently smooth fluid solution, to which I add four ounces of rosin (dissolved in naphthalene), and one quarter ounce of creosote oil. The 70 foregoing two preparations may be applied to the filler body in a heated condition and thus installed within a shoe bottom, or they may be rendered by an addition of water into an ordinarily flowing condition and admixed to the filler body cold and thus placed within the shoe bottom. Although not quite so quick-setting as when applied hot, the filler material installed by the cold method nevertheless sets readily for all practical 80 purposes. Or, in place of the former solutions, I may use two ounces of corn starch (or any other starch) swelled and dissolved with soda lye *i. e.* arabol or apparatin, etc., one ounce of glycerin, (this being an example of one of the well-known water-soluble fat-derived oily liquids, another of which is the olein oil of my application, Serial No. 591,207,) eight ounces of rosin (dissolved in naphthalene), three ounces of petroleum tailings, one half ounce of Wilmington tar, or any combinations of like materials which will provide a tenacious, elastic binding medium.

Certain of the foregoing binders are 95 covered also in my copending applications Ser. No. 432,083, filed May 11, 1908, now Patent No. 1,032,312, dated July 9, 1912, and Serial No. 591,207, filed November 7, 1910, now Patent No. 1,134,931, dated April 6, 1915. 100

The mixing of the filler-body material with the binder can be done by hand or with ordinary rotating machinery for this purpose, and when thoroughly admixed to a pasty condition, it can be spread easily with 105 a tool in the shoe bottom.

The set material (when in a shoe-bottom cavity) composed of a highly resilient body-giving component and a like adhesive agent admixed as stated above to stick the mass 110

2
to the leather innersole and to hold the sheeted layer of filler material in a strong tenacious manner, is the result of my present invention and constitutes the said second feature of the invention.

A third novel feature of my new filler lies in its application within the shoe bottom by providing the operator with a special solution for immersing the working tool, 10 or a revolving roll which is traveling in a solution of a precipitant, so that when the filler material is spread within the shoe cavity, the revolving roll is not only leveling the material but is also uniting with it 15 at the same time a chemical precipitant which makes the binding fluid substantially insoluble by water and adds greatly to its protection during the wear of the shoe. This makes a homogeneous filler mass or 20 layer and is in no sense a multiple-layer shoe-sole structure, which latter is therefore expressly disclaimed herein.

Binding fluids can also be made to hold the coagulated parts together and to the shoe 25 bottom, which, upon setting, undergo sufficient chemical changes so as not to become readily soluble by ordinary exposure to water, which is especially the case with certain preparations of starch and those natural 30 mucilaginous gums which can be used to advantage for the present purpose (as covered, for example, in my patent before mentioned).

Another way to overcome this moisture 35 influence of the binding agent is the use within the cementitious preparation of a percentage of sticky resinous matter which, upon the drying and setting of the material, is preponderatingly large, to protect the 40 gelatinous base from dissolution by water under ordinary conditions (as covered, for example, in my copending application Serial No. 432,083, filed May 11, 1908).

That the principles as set forth in my 45 present invention may be brought about by a large and varied use of materials is very evident, and, although I do not prefer it, instead of using the ground coagulated oil, the filler-components of my new shoe-bottom 50 filler may consist of a gluey or gelatinous base treated with glycerin and oils in such a manner as to become a permanently highly resilient mass, such, for example, as compositions used for printers' rolls, which, when 55 ground and mixed with a cementitious fluid, will produce a material similar to a sulfureted oil as previously described.

My invention includes any natural or artificial spongy, resilient mass which can be 60 ground to proper size so as to become conformable as a special component of the filler mass, and it also includes any combination which would require or permit the changing of the solvents, as, for instance, whenever 65 water-absorbing components are used to

provide the filler body, a changing to a naphtha solution of the so-called rubbers which I mean to include rubber, gutta percha, or like materials (which would not injuriously affect the said filler body components) to 70 bind and cement and render waterproof the otherwise to moisture yielding or absorbing mass I consider would come clearly within the meaning of my present invention. I also wish to embrace various means, such as 75 fluffy, light weight materials to act as an additional body-giver to the resilient body forming mass. Ground or shredded leather is the best known material of this kind in the shoe-making trade. This may be added 80 while the coagulation of the rubbery matter is about to take place, by making the same very porous (like a sponge), or it may be added to the mixed ingredients as a cheapening agent. 85

My Patent No. 945,294, of January 4, 1910, provides for a filler made resilient with a comminuted filler body and a gelatinous highly resilient binding component; such material therefore would depend 90 mainly for its resiliency upon the binding means, but my present filler aims to increase the resiliency still further by providing a filler body which is highly resilient or cushion-like as well as the binder, so that 95 the use of the above described method and means for a filler material provides a long sought for cushion for the foot which is at the present time gained through felt with the so-called cushion innersoles. 100

My new filler material will enable the shoe manufacturer to use a light leather innersole, and between this and the outersole to place a perfect fitting layer of highly resilient material, greatly more so than the ordinary rubber of commerce, thereby gaining an unchangeable cushion as it does not oxidize, which is impossible with a felt innersole. 105

A layer of this new resilient filler may also be applied to the heel portion of a shoe, 110 thereby forming and providing additional ease to the foot of the wearer which is now sought for by the use of rubber heels.

Having described my invention, what I claim as new and desire to secure by Letters 115 Patent is:

1. A shoe filler, comprising a resilient body of coagulated oil in a dissected condition held together in a permanently and highly resilient, cushion-like, adhesive and cohesive condition with a permanently resilient, sticky, cementitious binder which permits the filler to constitute a cushion in a shoe-bottom. 120

2. A shoe filler, comprising a body of dissected, coagulated oil and a permanently sticky cementitious binder, united in a sufficiently plastic, spreadable mass to be spread in a thin layer in a shoe-bottom to constitute a highly yieldable cushion for the foot. 125 130

3. A shoe filler, comprising a body of comminuted, coagulated oil united in a plastic, moldable mass by a cementitious binder of a gelatinous nature and having a resinous component, the mixture, when set, having a permanently and highly resilient cushion-like character adapted to constitute a cushion for a shoe-bottom.
4. A shoe filler, comprising a highly resilient body-giving component united with an adhesive resilient cementitious binder to a plastic condition spreadable in a shoe-bottom before setting, and having, when set, a highly resilient, cushion-like, strongly adhesive and cohesive and unchangeable character freely yielding in all directions to pressure but without disturbing its strong cohesiveness, said body-giving component consisting at least in part of coagulated oil in a fragmentary condition, and the binder serving to hold the fragments together and in place in a shoe.
5. A shoe filler, comprising a fragmentary spongy resilient body united in a permanently resilient, light mass by a binder containing a solvent noninfluencing to said body component, said binder uniting the fragmentary body material into a moldable plastic mass substantially waterproof.
6. A shoe filler, comprising an unchangeable, spongy, resilient, strongly coherent mass in a plastic, moldable condition and permanently adherent to leather.
7. A shoe filler, comprising a spongy, resilient mass, permanently adherent to leather,
- plastic and spreadable in a shoe-bottom before setting, and having, when set, a tenacious cohesiveness and a highly resilient, cushion-like and unchangeable character capable of constituting a cushion for a shoe-bottom.
8. A shoe filler, comprising a spongy, resilient mass in a plastic and spreadable moldable condition, held together by a cementitious binder in a cushion-like condition capable of constituting the cushion of a cushion-shoe.
9. A shoe filler, comprising a highly resilient, spongy and cushion-like mass sufficiently sticky to adhere to leather and strongly cohere throughout the mass, said mass having a pasty condition and spreadable in a shoe-bottom before setting, and consisting of fluffy, light-weight ingredients held together with a permanently resilient adhesive cement, so as to be capable of constituting the cushion of a shoe bottom.
10. A shoe filler, comprising a moldable body adapted to be impressed into and fill a shoe-cavity, and a top dressing united therewith to set the same to a condition substantially insoluble by water.

In testimony whereof, I have signed my name to this specification, in the presence of two subscribing witnesses.

ANDREW THOMA.
